UNITED STATES PATENT OFFICE.

LUTHER T. MATHER, OF SPRINGFIELD, MASSACHUSETTS.

PROCESS OF MAKING BRUSHES.

1,259,031.

Specification of Letters Patent. Patented Mar. 12, 1918.

Application filed January 18, 1915. Serial No. 2,956.

To all whom it may concern:

Be it known that I, LUTHER T. MATHER, a citizen of the United States of America, and resident of Springfield, in the county of 5 Hampden and State of Massachusetts, have invented certain new and useful Improvements in Processes of Making Brushes, of which the following is a full, clear, and exact description.

10 This invention relates to improvements in rotary brushes such as are extensively used in shoe factories and which are in the nature of improvements on patents of Phillips, dated Aug. 7th, 1899, No. 642,484, and Lars- 15 son, dated Jan. 8, 1901, No. 665,832.

In these patents the brush has been composed of brush strips produced by applying and stitching strip tape transversely and in then doubled relation to brush stock and in then 20 winding the same helically on a hub therefor and confining the portions of the brush strip adjacent and in engagement with the hub under pressure, thereon.

The brushes so made have not been a satisfactory product inasmuch as under the 25 centrifugal action produced by high rotation of the brushes in use, the bristles or brush stock, by reason of insufficient anchorage have loosened and been thrown out 30 whereby the life of the brush and its efficiency while in use have been entirely inadequate.

The present invention consists in a process 35 for the making of a brush of the general character set forth in the aforesigned patents, and by the exercise of which the bristles, horse hair or other brush stock included will remain securely bound in the central body or hub of the brush during the wearing life 40 of the brush, and until entirely reduced and worn away by use without any liability of loosening and detachment.

The invention is described in conjunction 45 with the accompanying drawings and is set forth in the claim.

In the drawings:—

Figure 1 is a face view of a short portion of indefinite length of a brush strip such as that included in the rotary brush of 50 the kind to which this invention relates.

Fig. 2 is a side view of a brush bundle.

Figs. 3 and 3^a are cross sectional views as taken on line $x-x$, Fig. 1, showing the employment, as may be variously adopted, of 55 single and double tapes.

Fig. 4 is a plan view showing the brush

strip coiled and as being subjected to the immersing and saturating action of the liquid pitch, the employment of which forms part of this process. 60

Fig. 5 is a sectional view as taken on line 5—5, Fig. 4.

Fig. 6 is a sectional view centrally through the completed brush.

In carrying out this process, I produce 65 the brush strip by the applying and stitching of strip tape a in doubled relation and at opposite sides of the bristles or horse hair, Tampico fiber or whatever brush stock or combination of brush stocks may be employed, and more or less in accordance with 70 the procedure under the aforementioned Phillips and Larsson patents.

The tape strip having a length sufficient 75 for the making of one or several brushes is then wound to involute curved form to form a bundle A, as represented in Figs. 2, 4 and 5, the same being temporarily tied by string b .

A pan D or shallow receptacle forms a 80 part of the apparatus appropriately employed and into which is supplied, in sufficient quantity, a heavy liquid solution d , which as provided by me is composed of what is commercially known as Burgundy 85 pitch and alcohol, in proportions of about 37 pounds of the pitch to 3 gallons of the alcohol.

The tape inclosed or butt end portion of 90 the brush strip bundle is set into the receptacle as represented in Figs. 4 and 5 and left therein for a short time but sufficiently long for the heavy pitch solution to thoroughly permeate the tape and the portions 95 of the brush stock connected therewith.

The bundle removed from the receptacle containing the pitch solution is then untied and unwound and hung up, subject to the partially drying and hardening action of the atmosphere for a considerable time, say for 100 two or three days.

The brush strip of sufficient length for one 105 rotary brush is then wound helically on the hub G, subjected to pressure resisted by the permanent flange g and then the detachable head or cap G² is screwed or otherwise secured on the hub confining the wound brush strip securely in its place,—the marginal portions of the head or cap G² forming the annular confining flange opposite the permanent flange g .

The pitch saturated and intimately com-

mingled with the tape and the portions of the brush stock connected therewith and inclosed thereby is effective in rendering the completed brush a perfectly satisfactory and acceptable commercial article and one not open to the fault heretofore existing of liability of loosening and detachment of the hair or bristles at any time during the life and use of the brush.

10 It is necessary that the pitch will reach all the fibers and a positive anchorage be obtained, and to this end the following action of the pitch upon the fibers and binding tape is repeatedly varied by the alteration 15 of the form of the combined strip. The strip is first placed in involute form in pitch, when the inner face of the strip will be slightly compressed and the outer face will be slightly stretched, and the fibers will 20 be rolled on themselves to positions different from that assumed when the strip is extended or without short curves.

When the coil is removed and straightened out, the fibers tend to resume their 25 natural positions, against unequal strip tension, and the tension of the walls of the strip becomes equal.

When the partially dried, pitch impregnated, brush strip is wound in helical form 30 upon the hub and placed under compression, a second change in the tension and relations of the brush fibers and strip walls takes

place, with the result that the pitch, still plastic, is forced into more intimate contact with the anchored fiber ends.

35

In other words, the repeated change in the strip form during the manufacture of the brush develops what may be termed a kneading action of the strip walls upon the anchored fiber ends, and this kneading action tends to increase the degree of penetration of the pitch, upon the strip and the faces of the fibers.

40

I claim:—

The process of brush making consisting in 45 sticking a quantity of brush fibers to a flexible tape to form a flexible brush strip, coiling said brush strip in involute form, immersing said involute coil in a solution of pitch and alcohol so that the strip and the 50 brush fiber ends engaged therewith are impregnated by the pitch, removing the impregnated coil from the pitch solution and unwinding the coil and allowing it to partially dry, coiling the partially dried strip 55 in helical form around a hub, and maintaining said helically coiled strip under compression.

Signed by me at Springfield, Mass., in presence of two subscribing witnesses.

L. T. MATHER.
